UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,591, dated August 28, 1894.

Application filed July 31, 1894. Serial No. 519,097. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of heraldic ornaments having a shield with cross bar, 10 and a star in the center, and ornamental scrolls at the sides and top of said ornaments, and cross sprays of leaves running under said ornaments, as represented in the accompanying drawing. The ornaments are placed at 15 uniform distances apart over the surface of the paper. The border or upper portion of the design is also formed of heraldic orna-

ments, and sprays of leaves crossing at the bottom of said ornaments, the said ornaments being connected by pendent ribbons from an ornamental frame which forms a series of connected rectangular - shaped panels as shown in the drawing.

What I claim is—

1. The design for wall paper herein shown and described.
2. In the design for wall paper, the border herein shown and described.

Witness my hand this 28th day of July, 1894.

CHARLES BOOZE.
